UNITED STATES PATENT OFFICE.

EMERY BAYARD, OF ROCHESTER, NEW YORK, ASSIGNOR TO UNITED SHOE MACHINERY COMPANY, OF PATERSON, NEW JERSEY, A CORPORATION OF NEW JERSEY.

APRON FOR SHOE-STITCHING MACHINES.

No. 906,092.

Specification of Letters Patent.

Patented Dec. 8, 1908.

Application filed December 6, 1905. Serial No. 290,561.

To all whom it may concern:

Be it known that I, EMERY BAYARD, a citizen of the United States, residing at Rochester, in the county of Monroe and State of New York, have invented certain new and useful Improvements in Aprons for Shoe-Stitching Machines; and I do hereby declare the following to be a full, clear, and exact description of the invention, such as will enable others skilled in the art to which it appertains to make and use the same.

The present invention relates to improvements in aprons for shoe-stitching machines.

In a shoe-stitching machine of the familiar curved-needle lock-stitch type the looper, in moving about the needle to lay the thread in the barb thereof, operates in close proximity to the upper of the shoe which is being stitched, and unless a guard of some kind is interposed the operator, in guiding the shoe, will often hold it in such a position as to cause it to be struck by the looper. As the looper is usually moist with oil or wax such an accidental contact soils and damages the shoe when it is of canvas or light colored leather.

One object of the present invention is to produce a guard or apron which will prevent such contact between the work and the looper without inconveniencing the operator in guiding the work.

Another object of the invention is to produce an apron which will intercept oil or wax thrown from the vibrating take-up to prevent soiling of the shoe thereby.

In carrying out this invention the body or main part of the apron is made of thin and stiff sheet metal so as to obtain the necessary strength without substantially reducing the limited space in front of the sewing mechanism which is available for the necessary movements of the shoe in guiding it, while the upper part of the apron consists of a small piece of thin and flexible leather, which is held in such position in front of the looper as to be interposed between the looper and the work. The leather may be pressed against the looper without injury to the latter, and therefore it reduces only by its actual thickness the available space in front of the looper. Other features of the invention will be described in connection with the description of the illustrated embodiment of the invention.

In the drawings Figure 1 is a front eleva-

tion and Fig. 2 a side elevation of the improved apron, showing the adjacent portions of a shoe-stitching machine to which it is attached, and Fig. 3 is a plan view of the apron with the flexible portion removed.

The invention is illustrated as applied to a shoe-stitching machine of the type commonly known as the Goodyear rapid outsole stitcher, provided with an extension-edge attachment said machine being illustrated with substantial accuracy in the patent to French and Meyer, No. 473,870; dated April 26, 1892.

The body 1 of the apron is made of sheet metal, and is rigidly secured, for convenience, on an upright 2 forming part of the extension-edge attachment, having a slotted lug 3 engaged by a washer 4 and a screw 5 screwed into the upright 2. The body of the apron extends down in front of the take-up 6 of the stitcher. The upper extremity of the body 1 is provided with ears 7 bent inward so as to form a socket 8 and constitute a holder for the flexible portion of the apron. In the socket 8 is held a strip 9 of thin leather or other flexible material which is located in front of the looper 10 and interposed between the looper and the work. As the holder is located adjacent to the looper only a small piece of leather is necessary, and it need not be thick and stiff. When the upper end of the strip 9 is worn through the strip may be reversed and the other end used until worn out. The strip 9 may be readily removed for convenience in exchanging it or in threading or cleaning the looper, and the body of the apron need never be removed and may form a permanent fixture.

Aprons for shoe-stitching machines having a portion interposed between the looper and the shoe-upper have been used heretofore, but such aprons have always so far as the inventor is aware, been made of a single piece of leather, which, in order to have the necessary stiffness, must be thick and of good quality. The thickness is objectionable since it causes the apron to occupy more of the space in front of the mechanism, and, since the whole apron must be renewed when the upper extremity is worn out, such aprons are expensive and inconvenient.

Having thus described the invention, what is claimed is:—

1. An apron for shoe stitching machines comprising a holder located adjacent to the

looper, and a removable piece of flexible sheet material held therein between the looper and the work to prevent accidental contact therebetween, substantially as described.

2. An apron for shoe stitching machines comprising a holder located at the front of the machine and a reversible strip of flexible sheet material held therein between the 10 looper and the work to prevent accidental contact therebetween, substantially as described.

3. An apron for shoe stitching machines, comprising a guard of sheet metal located in 15 front of the machine and provided at its upper end with a holder, and a removable piece of flexible sheet material held in the holder between the looper and the work to prevent accidental contact therebetween, substantially 20 as described.

4. An apron for shoe stitching machines

comprising a guard of sheet metal located in front of the take-up and provided with a flexible leather extension located in front of the looper, substantially as described.

5. An apron for shoe stitching machines comprising, in combination with sewing instrumentalities including a needle and an awl operating on opposite sides of the work and a looper located on the awl side of the work, a 30 holder located on the awl side of the work and adjacent to the looper, and a removable piece of flexible sheet material held therein between the looper and the work to prevent accidental contact therebetween, substantially 35 as described.

In testimony whereof I affix my signature, in presence of two witnesses.

EMERY BAYARD.
